UNITED STATES PATENT OFFICE.

CATHERINE O. ORWIG, OF SMITHFIELD, ILLINOIS.

COMBINED STEP-LADDER AND IRONING-BOARD.

1,035,998.

Specification of Letters Patent. Patented Aug. 20, 1912.

Application filed February 14, 1912. Serial No. 677,475.

To all whom it may concern:

Be it known that I, CATHERINE O. ORWIG, a citizen of the United States, residing at Smithfield, in the county of Fulton and State of Illinois, have invented certain new and useful Improvements in Combined Step-Ladders and Ironing-Boards, of which the following is a specification, reference being had to the accompanying drawings.

10 This invention relates to new and useful improvements in combined step ladders and ironing tables and my object is to provide a device of this character which is readily adapted for use in either capacity and which 15 may be compactly folded for storage purposes.

A further object of the invention resides in providing a board which is slidably disposed on the supporting means for the ladder and a still further object resides in providing a folding support for the board whereby said board and folding support may be readily disposed between and secured to the supporting means for the 25 ladder to be entirely out of use.

Still another object of the invention is to provide a device which is simple in construction, inexpensive to manufacture and one which is very efficient and useful in 30 operation.

With these and other objects in view, my invention consists in the novel features of construction, combination and arrangement of parts as will be hereinafter referred to 35 and more particularly pointed out in the specification and claims.

In the accompanying drawings forming a part of this application, Figure 1 is a side elevation of my device set up for use as an 40 ironing table; Fig. 2 is a bottom plan view thereof; Fig. 3 is a perspective view of the device set up for use as a step ladder and showing the ironing table attachment folded in its inoperative position; Fig. 4 is a 45 vertical section as seen on line 4—4 of Fig. 1; and Fig. 5 is a section as seen on line 5—5 of Fig. 2.

In carrying out my invention, I shall refer to the drawings, in which similar reference characters designate corresponding parts throughout the several views and in which—

1 indicates a ladder comprising side rails 2 between which are secured the step pieces 50 3, said ladder being adapted for upright support by means of the prop 4 pivotally

carried on a round 5. This round 5 is held between the upper ends of the side pieces 2 and the outward swinging movement of said prop is limited by means of a back piece 60 6 secured to the rear edges of said side pieces at their upper ends.

The side rails of the prop 4 for the ladder, are held together by means of a lower round 7 and an intermediate round 8, and a board 65 9 is carried on said round 8 by being provided on its under face with the spaced guide rails or bars 10 through which extends said round 8. This board 9 is, therefore, 70 slidably carried on the supporting means for the ladder, so that the same may be swung vertically thereof, as shown in Fig. 3 or projected therefrom, as shown in Fig. 1, and I have provided a supporting means for the board when disposed in its horizontal 75 and projected position.

The lower round 7 of the prop 4 has pivotally mounted thereon the bars 11 which are of any suitable length and held together at their opposite ends by means of an additional round 12, while said latter round has pivotally mounted thereon an additional frame 13 comprising a pair of side rails secured at their outer ends by means of a cross bar 14 and held together adjacent the inner 80 end by means of a round 15. The bars 11 forming a frame in themselves are adapted to rest on the floor while the frame 13 is adapted to extend vertically thereof to receive on the upper cross bar 14, the under face 85 of the board 9 adjacent its outer end and in order to support the frame 13 in its vertical position, I provide a pair of bracing arms 16 on the round 15. These bracing arms are pivotally mounted on said round 15 and the 90 free ends of the same are provided with notches 17 adapted to engage the additional round 18 secured between the bars 11. From this construction, it will be seen that when the board 9 has been disposed in its projected position and the supporting frame set up in the position shown in Fig. 1, said board will be supported in position for use. In order to prevent, however, the sliding movement of said board during the use thereof, the under face of the same adjacent its inner end is provided with a groove 19 which is adapted to receive the round 8, as shown in Fig. 5, when the board is properly disposed in its extended position.

From the above description, it will be seen that the device may be readily disposed

in position to be used as an ironing table at any time desired, but should it be found necessary to use the device as a ladder and undesirable to allow the device to remain standing as an ironing table, the table portion of the device may be readily folded. This is accomplished by first raising the board 9 from the position shown in Fig. 1 and sliding the same on the round 8 until 10 said board is disposed in a substantially vertical position on said round, whereupon the bracing arms 16 are disengaged from the round 18 and the bars 11 together with the frame 13 folded up against the board 9 and 15 between the side rails of the prop. This position may be readily seen from the disclosure made in Fig. 3 of the drawings, and in order to retain the device in its folded position, the pivoted latch members or keepers 20 are provided on the prop 4 and adapted to be disposed in position to engage the top rail 14 of the rail 13. When so positioned, the table portion of the device will 25 be securely held between the prop legs of the ladder and the device wholly used as a ladder.

From the foregoing, it will be seen that I have provided a simple, inexpensive and efficient means for carrying out the objects 30 of my invention, and while I have particularly described the elements most well adapted to perform the functions set forth, it is obvious that various changes in form, proportion and in the minor details of construction may be resorted to for successfully carrying my invention into practice without sacrificing any of the novel features or departing from the scope of the invention.

Having thus described this invention, 40 what is claimed is:—

1. In a device of the class described, the combination with a ladder and prop therefor comprising a pair of supporting standards, a transverse bar connecting the same; of a 45 board slidably arranged on said transverse bar, a folding frame pivotally carried between said standards and adapted to support said board in its extended position, and pivoted latch members carried on said standards to lock said board and frame in folded 50 position between the standards.

2. In a device of the class described the combination with a ladder, and prop therefor comprising a pair of standards having a transverse bar connecting the same; of a 55 board slidably arranged thereon, a pair of bars pivotally mounted on the lower ends of said standards, a frame pivotally connected to the opposite ends of said bars, a transverse rod connecting said bars, and bracing 60 arms pivotally carried on said frame and adapted to engage the last referred to rod to support said frame in a vertical position, whereby said board may be in turn supported in its extended position. 65

3. In a device of the class described the combination with a ladder, and prop therefor comprising a pair of standards having a round connecting the same; of a board provided with guide rails on the under face 70 thereof through which said round extends, a folding supporting frame for the board pivotally carried between said standards, and means to lock said board and supporting frame in folded position between the 75 standards.

4. In a device of the class described, the combination with a ladder, a prop therefor comprising a pair of standards, a transverse bar connecting said standards; of a 80 board, a pair of guide rails secured to the under face of said board and spaced therefrom, said guide rails receiving therein the transverse bar connecting the standards to pivotally and slidably mount said board between the standards, the under face of said board being provided adjacent its one end with a groove adapted to receive said transverse bar therein, a folding supporting frame pivotally carried between said standards at 85 the lower ends thereof, and means to support one section of said folding frame at right angles to the other section thereof, whereby one of said sections will be disposed in position to receive the outer portion of 90 said board thereon.

In testimony whereof I hereunto affix my signature in the presence of two witnesses.

CATHERINE O. ORWIG.
